UNITED STATES PATENT OFFICE.

ALBERT STEFFIN, OF NEW BEDFORD, MASSACHUSETTS, ASSIGNOR TO THE MOUNT WASHINGTON GLASS COMPANY, OF SAME PLACE.

DESIGN FOR A VESSEL.

SPECIFICATION forming part of Design No. 22,171, dated January 31, 1893.

Application filed February 23, 1892. Serial No. 422,584. Term of patent 7 years.

To all whom it may concern:

Be it known that I, ALBERT STEFFIN, of New Bedford, in the county of Bristol and State of Massachusetts, have invented and produced a new and original Design for a Vessel, of which the following is a specification, reference being had to the accompanying drawings, showing a part thereof.

Figure 1 is a top plan view of a vessel showing my design; Fig. 2, a sectional side elevation of the same.

The leading feature of my design consists in a vessel having a veined base, the cup portion rising upwardly from the base and being indented on its edge to form alternate broad and narrow projections, the outer surface of the cup being grooved from its junction with the base to the narrower projections.

A is the base grooved at a to give a leaf-like effect.

B is the cup rising upwardly and outwardly from base A. The edge of the cup is indented at b to produce the alternate broad projections b' and narrow projections b². From the narrow projections b², grooves b³ extend to the bottom of the cup, dividing the outer wall of the cup into leaf like sections b⁴ of which the projections b' are the tips or upper ends.

What I claim is:

The design for a vessel herein shown and described.

ALBERT STEFFIN.
